COMBINED ROSE AND KNOB FOR A DOOR LOCK

Andrea Spadini, Rome, Italy, assignor to The Yale & Towne Manufacturing Company, Stamford, Conn., a corporation of Connecticut

Application June 15, 1956, Serial No. 41,916

Term of patent 7 years

(Cl. D50—3)

Fig. 1.

Fig. 2.

Fig. 1 is an end view of a combined rose and knob for a door lock embodying my new design.

Fig. 2 is a bottom view showing the combined rose and knob.

I claim:

The ornamental design for a combined rose and knob for a door lock, substantially as shown.
